UNITED STATES PATENT OFFICE.

JOHN C. GLENN, OF ERIE, PENNSYLVANIA.

STEAM-ENGINE.

specification of Letters Patent. Patented Jan. 14, 1919.

1,291,478.

Application filed February 16, 1918. Serial No. 217,633.

To all whom it may concern:

Be it known that I, JOHN C. GLENN, a citizen of the United States, residing at Erie, in the county of Erie and State of Pennsylvania, have invented certain new and useful Improvements in Steam-Engines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to steam engines, and particularly to that class thereof known as uni-flow engines, and consists in providing by certain clearance chamber mechanism by means of which a sufficient clearance is automatically provided when the engine is not 20 used in association with a condenser.

The features of applicant's invention are hereinafter fully described and pointed out and are illustrated in the accompanying 25 drawings in which:—

Figure 1, is a plan view partially in elevation and partially in section showing my invention installed thereon.

Fig. 2, is a fragmentary transverse section 30 of the same on the line $x-x$ in Fig. 1.

In these drawings A indicates an engine cylinder having inlet valve housings A' at the ends thereof which communicate in the usual manner (not shown) with the interior of the cylinder, and central piston controlled exhaust ports a , which communicate through the cylinder wall into the usual exhaust belt A². B indicates the piston therein, and B' indicates the piston-rod; C indicates a clearance chamber on the side of the cylinder A which communicates with the interior of the cylinder A by means of a valve controlled opening C'. To close this opening C' I provide a valve D which is 40 adapted to seat against a valve-seat d around the outer end of the opening C'. The valve D is provided with a stem D' which projects outwardly through a cover plate E, on the inner side of which there is a boss E' which 45 projects into the clearance chamber C, and is provided on its inner end with a valve-seat e against which the rear side of the valve D will seat when the valve D is opened as hereinafter described, so as to prevent 50 any leakage around the valve-stem D'. 55

For operating and controlling the valve D

I provide a cylinder F which I preferably secure against the exhaust belt A², and which communicates therewith through the opening f; and within the cylinder F I place 60 a piston F'. On the cover-plate E are ears e' e' in which is pivoted a lever G, and pivoted to said lever G and said piston F' is a link-bar G'. The lever G is provided with a cam-arm G² which engages the end of the 65 valve-stem D so that when the engine is operating in association with a condenser, in the manner in which condensers are usually operated, the partial vacuum maintained in the condenser is communicated to 70 the exhaust pipe H, exhaust belt A² and opening f, to the cylinder F, and operates to draw the pistons in said cylinder to the middle portion of said cylinder F, which, through the link-bars G' actuate the cam-arms G² to force the valves D against the 75 valve-seats d , and thereby close the opening C' from the cylinder into the clearance chamber C, as when the engine is operated 80 in such a manner the partial vacuum is also communicated to the interior of the cylinder when the ports a are uncovered by the piston B, thereby reducing the pressure in that end of the cylinder A below atmospheric pressure, so that the return movement of the piston B will not cause an undue compression 85 therein.

Now should the partial vacuum in the condenser, and consequently in the exhaust pipe H and exhaust belt A², be lost, as is the 90 case when the power plant has been completely shut down, and the engine is started, the pressure of the exhaust steam in the exhaust belt A², communicated through the opening f into the cylinder F, will operate 95 the pistons F' outwardly, and thereby, through the link-bars G' and levers G allow the valves D to be forced open by the compression caused within the cylinder A by the return movement of the piston B, so that 100 the fluid thus compressed may escape into the chamber C, and as the valve D remains open as long as the condenser is out of operation, the fluid compressed into the clearance chamber C can flow back through the 105 opening C', when the piston B moves forward and uncovers the exhaust ports a to that end of the cylinder. To increase the flow of the compressed fluid from the clearance chamber C back into the cylinder A, I 110 provide a cylinder J which communicates with the clearance chamber C, and within

the cylinder J I place a piston J', which is provided with an annular shoulder j therearound, which engages a reversed like shoulder within the cylinder J, so as to limit the inward movement of the piston J', and I provide a leak duct j', so that compressed fluid may flow inward to the annular shoulder during the period of compression, and gradually escape therefrom when the compression is released, and thereby cushion the inward movement of the piston J'.

Behind the piston J' in the cylinder J I provide a suitable resilient means to resist the outward movement of the piston J, and for this purpose I preferably use a spring K, and a screw K', mounted in the cover K² of the cylinder J, by means of which the pressure behind the piston J' may be regulated. The operation of the piston J' is such that when the valve D is opened, as hereinbefore described, and fluid is forced through the opening C' into the clearance chamber C, the piston J' will be forced outwardly in the cylinder J, and upon the release of the pressure by the uncovering of the exhaust ports a the counter pressure behind the piston J' will force the piston J' inward thereby forcing fluid in the chamber C back into the cylinder A. This return flow of fluid from the chamber C into the cylinder A will commence as soon as the pressure in the cylinder A becomes less than in the chamber C. As soon as the condenser again begins to work and a partial vacuum is again communicated therefrom to the cylinder F, the valves D will be closed and the clearance chamber C will, for the time being cease to be operative.

Having thus described my invention, and illustrated suitable mechanism for embody-

ing the same, I do not desire to limit myself to the exact construction shown and described, as it is obvious that many other forms of mechanism can be employed without departing from the scope of my invention.

Therefore what I claim as new and desire to secure by Letters Patent is:—

1. The combination with a uni-flow engine, of an engine cylinder, a clearance chamber thereon, an opening from the interior of said cylinder to said chamber, a valve to control said opening, a stem on said valve, a cam-lever engaging said stem, a cylinder communicating with exhaust of said engine, a piston in said cylinder, and a link-bar connecting said piston and said cam-lever, substantially as set forth.

2. The combination with a uni-flow engine, of a clearance chamber, a cylinder in communication therewith, a piston in said cylinder, and elastic means to force said piston toward said chamber, substantially as set forth.

3. The combination with a uni-flow engine, of a clearance chamber, a cylinder in communication with said chamber, a piston in said chamber, a spring behind said piston to force the same inwardly, and means to adjust the pressure of said spring, substantially as set forth.

4. The combination with a uni-flow engine, of a clearance chamber, a cylinder in communication therewith, a piston in said cylinder, means to cushion the inward movement of said piston, and elastic means behind said piston to force the same toward said chamber, substantially as set forth.

In testimony whereof I affix my signature.

JOHN C. GLENN.
